Fig. 14.

FIG. 1 is a front view in elevation of a photographic enlarger showing one embodiment of my new design;

FIG. 2 is a left side elevational view of the design shown in FIG. 1;

FIG. 3 is a right side elevational view of the design shown in FIGS. 1 and 2;

FIG. 4 is a top plan view of the design shown in FIGS. 1-3;

FIG. 5 is a rear elevational view of the design shown in FIGS. 1-4;

FIG. 6 is a bottom plan view of the design shown in FIGS. 1-5;

FIG. 7 is a cross-sectional view taken along lines 7-7 of FIG. 3;

FIG. 8 is a front view in elevation of a photographic enlarger showing another embodiment of my new design;

FIG. 9 is a left side elevational view of the design shown in FIG. 8;

FIG. 10 is a right side elevational view of the design shown in FIGS. 8 and 9;

FIG. 11 is a top plan view of the design shown in FIGS. 8-10;

FIG. 12 is a rear elevational view of the design shown in FIGS. 8-11;

FIG. 13 is a bottom plan view of the design shown in FIGS. 8-12; and

FIG. 14 is a cross-sectional plan view taken along lines 14-14 of FIG. 10.

This is a continuation of design applications Ser. Nos. D. 14,747 and D. 14,750, both filed Dec. 2, 1968, now abandoned.

I claim:

The ornamental design for a photographic enlarger, as shown and described.
